[57] ABSTRACT

A snowplow blade mounted at the forward end of a vehicle is set obliquely with respect to the forward direction of travel, the snowplow blade presenting a forwardly directed concave face defining a lower scraping edge, a top edge, and respective leading and trailing lateral edges, the shape and setting of the blade being such that a line extending diagonally across the blade face from the leading end of the lower scraping edge to the trailing end of the top edge intersects the lower scraping edge at an angle which is greater than the acute angle subtended between the lower scraping edge and said forward direction of travel.

SNOWPLOW BLADE

This invention relates generally to snowplows and to blade or moldboards therefor. The invention is concerned particularly with snowplows designed to operate at high speeds.

When considering the operation of snowplows it is appropriate to consider two ranges of operating speeds in which the snow flow patterns across the blade face are quite different. In the lower of the ranges, typically up to 15 - 20 m.p.h., the snow encountered by the blade is not lifted to the top of the blade but is simply carried sideways with a rolling action and deposited just beyond the trailing edge of the blade. In the upper range, typically above 15 - 20 m.p.h., the velocity is sufficient to cast the snow laterally from the blade.

The problems of blade design are different for the two speed ranges. In the lower speed range the blade simply pushes the snow and its shape is relatively unimportant. In the upper speed range the cast distance is of major concern as also is the problem of minimizing the impairment of visibility through snow passing over the top edge of the blade, and in practice a compromise is usually sought.

It is one object of the present invention to provide a blade construction which ensures maximum visibility at high speeds.

It is another object of the present invention to provide a blade construction which ensures maximum visibility at high speeds and which is designed to increase the distance of cast.

Accordingly the invention provides in combination with a vehicle having a forward direction of travel, a snowplow blade mounted at the forward end of the vehicle and set obliquely with respect to the forward direction of travel, the snowplow blade presenting a forwardly directed concave face defining a lower scraping edge, a top edge, and respective leading and trailing lateral edges, the shape and setting of the blade being such that a line extending diagonally across the blade face from the leading end of the lower scraping edge to the trailing end of the top edge intersects the lower scraping edge at an angle which is greater than the acute angle subtended between the lower scraping edge and said forward direction of travel.

A feature of the invention is that the snowplow blade has an extension projecting laterally from said trailing lateral edge, the extension presenting a forwardly directed concave face contiguous with said concave face of the blade and subtending an obtuse angle therewith whereby to intersect and deflect snow directed across said trailing lateral edge of the blade face.

In order that the invention may be readily understood, two embodiments thereof will now be described by way of example with reference to the accompanying drawings, in which:

FIG. 1 is a side elevation of a snowplow provided with a moldboard or plowblade according to the present invention;

FIG. 2 is a plan view of the snowplow shown in FIG. 1;

FIG. 3 is a front perspective view of the plowblade;

FIG. 4 is a developed plan view of the plowblade;

FIG. 5 is a front perspective view of an alternative plow blade in accordance with the invention; and

FIG. 6 is a developed plan view of the plowblade shown in FIG. 5.

The snowplow illustrated in FIGS. 1 and 2 comprises a truck 10 having a mounting means 11 at its forward end by which a snowplow blade 12 is mounted on the truck. The blade 12 is set obliquely with respect to the forward direction of travel of the truck, at an angle θ , as indicated in FIG. 2. The blade 12 has a forwardly directed concave face 13 which defines a lower scraping edge 14, a top edge 15, leading and trailing lateral edges 16, 17, and an oblique edge 18 extending from the trailing end of the lower scraping edge 14 and intersecting the trailing lateral edge 17. The configuration of the blade is of critical importance, and for clear identification these edges are also identified by the same reference numerals in FIGS. 3 - 6.

The snowplow blade of FIGS. 1 - 4 also has an extension 19 projecting laterally from the trailing edge of the blade face 13, the extension presenting a forwardly directed concave face contiguous with the concave face of the blade and subtending an obtuse angle with it which varies from a maximum value at each end of the trailing edge 17 to a minimum value at an intermediate position. The snowplow blade of FIGS. 5 and 6 is generally similar to that of FIGS. 1 - 4, and is adapted to be mounted on the truck in the same way as the latter, but does not have the lateral extension 19 projecting from the trailing edge of the blade face. To simplify the description, the configuration of the simpler blade of FIGS. 5 and 6 will be described first.

Referring to FIGS. 5 and 6, the blade is arranged to be mounted so that its lower scraping edge 14 subtends an angle θ with the forward direction of travel; the width of path that the blade will clear is obviously given by $L \sin \theta$, where L is the length of the scraping edge 14. The blade is designed primarily for use at high speeds, that is to say at speeds of 20 m.p.h. and higher, and it is therefore an important requirement of the design that snow lifted across the blade face should not be lifted across the top edge 15 of the blade. Ideally the snow should be wholly diverted across the lateral trailing edge 17, as indicated by the snow flow lines X, Y, Z. As seen in the developed plan view of FIG. 6, this requirement is met if the extreme flow line Z, extending along the longitudinal line A-B, intersects the edge 17. Therefore the condition that snow should not be diverted over the top edge 15 is that a line AC extending diagonally across the blade face from the leading end A of the lower scraping edge to the trailing end C of the top edge should intersect the scraping edge 14 at an angle which is greater than the acute angle θ subtended between the lower scraping edge and the forward direction of travel (or the line A-B).

By providing the oblique edge 18 it is ensured that all snow intercepted by the scraping edge of the blade has to travel a substantial distance across the blade face.

Clearly the oblique edge must not intersect any of the flow lines. It therefore follows that the oblique edge 18 must subtend an obtuse angle with the lower scraping edge 14 which is greater than the complement of the angle θ .

The blade configuration shown in FIGS. 3 and 4 is essentially similar to that of FIGS. 5 and 6, and corresponding parts are denoted by the same reference numerals and letters. However, snow diverted across the trailing edge 17 of the blade face is caused to flow across the face of the extension 19, which is shaped so as to converge the snow flow lines. The extension is designed so as to increase the distance to which snow is

cast laterally from the snowplow. To this end the concave face of the extension subtends an obtuse angle with the concave face of the blade. It is found in practice that the maximum cast is achieved when this angle varies from a maximum value at each end of the trailing edge 17, to a minimum value at an intermediate position, the minimum value being between $(90^\circ + \theta)$ and $(115^\circ + \theta)$, where θ is the acute angle subtended between the lower scraping edge and the forward direction of travel.

What we claim as our invention is:

1. In combination with a vehicle having a forward direction of travel, a snowplow blade mounted at the forward end of the vehicle and set obliquely with respect to the forward direction of travel, the snowplow blade presenting a forwardly directed concave face defining a lower scraping edge, a top edge, and respective leading and trailing lateral edges, the shape and setting of the blade being such that a line extending diagonally across the blade face from the leading end of the lower scraping edge to the trailing end of the top edge intersects the lower scraping edge at an angle which is greater than the acute angle subtended between the lower scraping edge and said forward direction of travel, the concave face of the blade further defining an oblique edge extending from the trailing end of the lower scraping edge and intersecting said trailing lateral edge, the oblique edge subtending an obtuse angle with the lower scraping edge which is greater than the complement of said acute angle, the snowplow blade having an extension projecting laterally from said trailing lateral edge, the extension presenting a forwardly directed concave face contiguous with said concave face of the blade and subtending an obtuse angle therewith whereby to intersect and deflect snow directed across said trailing lateral edge of the blade face.

2. In combination with a vehicle having a forward direction of travel, a snowplow blade mounted at the forward end of the vehicle and set obliquely with respect to the forward direction of travel, the snowplow blade presenting a forwardly directed concave face defining a lower scraping edge, a top edge, and respective lead-

ing and trailing lateral edges, the shape and setting of the blade being such that a line extending diagonally across the blade face from the leading end of the lower scraping edge to the trailing end of the top edge intersects the lower scraping edge at an angle which is greater than the acute angle subtended between the lower scraping edge and said forward direction of travel, the snowplow blade having an extension projecting laterally from said trailing lateral edge, the extension presenting a forwardly directed concave face contiguous with said concave face of the blade and subtending therewith an obtuse angle which varies from a maximum value at each end of the trailing edge to a minimum value at an intermediate position, said minimum value being between $(90^\circ + \theta)$ and $(115^\circ + \theta)$ where θ is the acute angle subtended between the lower scraping edge and the forward direction of travel.

3. In combination: a snowplow blade and vehicle mounting means therefor, said vehicle mounting means being connected to the blade to set the blade obliquely with respect to a forward direction of travel, the snowplow blade presenting a forwardly directed concave face defining a lower scraping edge, a top edge, and respective leading and trailing lateral edges, the shape and setting of the blade being such that the line extending diagonally across the blade face from the leading end of the lower scraping edge to the trailing edge of the top edge intersects the lower scraping edge at an angle which is greater than the acute angle subtended between the lower scraping edge and said forward direction of travel, the snowplow blade having an extension projecting laterally from said trailing lateral edge, the extension presenting a forwardly directed concave face contiguous with said concave face of the blade and subtending therewith an obtuse angle which varies from a maximum value at each end of the trailing edge to a minimum value at an intermediate position, said minimum value being between $(90^\circ + \theta)$ and $(115^\circ + \theta)$ where θ is the acute angle subtended between the lower scraping edge and the forward direction of travel.
